METAL FENCE POST

Filed Jan. 25, 1935

UNITED STATES PATENT OFFICE

2,029,739

METAL FENCE POST

Edward Pavek, Minneapolis, Minn.

Application January 25, 1935, Serial No. 3,417

2 Claims. (Cl. 256—52)

This invention relates to a fence post and particularly to a metal fence post made of a plate or plate-like material. Metal fence posts are now widely used, particularly for wire fences. The wire fence most commonly used has quite a number of longitudinally extending spaced strands and these are connected at comparatively short intervals by wires extending at right angles thereto. In many wire fences the wires adjacent the ground are spaced closer together, the spacing of the wires often decreasing toward the ground.

It is an object of this invention to provide a fence post of simple and inexpensive form, the metal in which is most advantageously disposed for resisting the stresses and providing wire attaching means.

It is a further object of the invention to provide a post of angular shape in transverse cross section and made of plate-like material, said post having a zone along one edge of much less thickness than the remainder of the post, said zone having spaced notches cut therein at right angles to the length of the post, the portions between said notches being reversely bent to form a bight, said portion of reduced thickness being very easily bent.

It is another object of the invention to provide a post of angular form in transverse cross section and made of plate-like material, said post having a zone along one side of much less thickness than the remainder of the post, the same having transverse spaced notches cut therein at the upper portion of the post, the portions between said notches being reversely bent to form a bight and said thin portion at the bottom portion of the post being flat and disposed substantially parallel to the direction of the longitudinal strands of the fence to give more anchoring surface.

It is still another object of the invention to provide a post as set forth in the preceding paragraph, the lower portion of said thin zone having vertically extending tongues cut therein and bent outwardly having free lower ends beneath which the strands of the fence can pass and be held without bending or kinking, whereby all of the fence strands can pass along said post and be held without bending.

It is still another object of the invention to provide a fence post of angular form in transverse cross section and made of plate-like material, the same having a zone along one side of much less thickness than the remainder of the post, the same having spaced transverse notches cut therein, the portion between said notches being re-

versely bent to form a bight adapted to receive a resilient locking wire or rod, said bight having depressions pressed therein on its convex side around which said locking wire must pass, tension thus being placed on said locking wire to press the strands of the fence against the bottoms of said notches to prevent excessive vibration of the strands.

These and other objects and advantages of the invention will be fully set forth in the following description made in connection with the accompanying drawings, in which like reference characters refer to similar parts throughout the several views and in which:

Fig. 1 is a view in front elevation of the post showing the same in the ground with the fence attached thereto;

Fig. 2 is a plan view of a blank from which the post is cut;

Fig. 3 is a top or edge view of the blank shown in Fig. 2;

Fig. 4 is a plan view of another form of blank from which the post may be cut;

Fig. 5 is a top or edge view of the blank shown in Fig. 4;

Fig. 6 is a horizontal section taken on line 6—6 of Fig. 1;

Fig. 7 is a partial view in front elevation on an enlarged scale of the lower portion of the post;

Fig. 8 is a view in side elevation as seen from the right of Fig. 7;

Fig. 9 is a transverse section of a post of right angular form;

Fig. 10 is a perspective view of a portion of the post shown in Fig. 9 showing the manner of holding the fence wire;

Fig. 11 is a horizontal section on line 11—11 of Fig. 10 as indicated by the arrows;

Fig. 12 is a view in side elevation as seen from the right of Fig. 10 showing a different form of holding member;

Fig. 13 is a view in front elevation of the form of post shown in Figs. 9 and 10 illustrating a chicken wire secured thereto;

Fig. 14 is a view in front elevation of the post shown in Figs. 9 and 10 illustrating how the vertical wires of the fence may be received in the bight of the post; and

Fig. 15 is a horizontal section on line 15—15 of Fig. 14 as indicated by the arrow.

Referring to the drawings, in Figs. 4 and 5 a plate 20 is shown having portions or zones 20a at each side thereof of much less thickness than the remainder or central portion of the plate. The

plate can be rolled to the form shown while it is still hot in the rolls. Said plate can be cut longitudinally on the lines 20b shown in Fig 4 to form four tapered posts. These posts can be 5 pressed into the shape shown in Figs. 1 and 6. A post is then formed of substantially U-shape in transverse cross section, the sides diverging slightly toward the open side of the post. A zone thus extends along one side of the post 10 which is of much less thickness than the remainder of the post.

In Figs. 2 and 3 a plate 21 is shown which has a central portion 21a which is of much less thickness than the remainder of the plate. This plate 15 can be cut along the line 21b in Fig. 2 to form two non-tapering posts and the post can be pressed into the shape shown in Fig. 6 or into the right angular shape shown in Figs. 9 and 10. The post will have a zone of much less thickness along one 20 side and this zone will have cut therein spaced notches. In the post 22 shown in Figs. 1 and 6 the thin edge portion 22a is shown reversely bent toward the rear side of the post to form a small trough or bight. This thin edge portion or zone 25 is provided with a series of notches 22b extending transversely and extending along the length of the post. The portion between these notches is bent to form the bight 22a. At the lower or ground end of the post the thin portion is disposed 30 transversely of the post or parallel with the direction of the fence wires secured to the post. The thin portion is thus flat and unbent and acts to give a greater anchoring surface to the lower portions of the post, which is driven into the ground. The part of the flat thin portion adjacent the ground is provided with a series of struck up tongues 22c. These tongues have free lower ends and parallel sides and are 35 pressed forwardly. The strands 23 of the fence can pass beneath these tongues and the tongues can then be pressed inwardly at their lower ends by being tapped with a hammer or in any other desirable manner and the wires 23 will be held in position without being bent or kinked. The 40 wires 24 of the fence above the lower wires 23 will be disposed in the notches 22b and a locking wire or rod 25 which is preferably of resilient material will be disposed vertically in the bight 22a, the same passing in front of the wires 24 and holding the same in position.

In Figs. 9 to 11 and 13 and 15 a post of right angular form is shown and the same is not tapered. Such a post can be formed from the blank in Fig. 3. This post 26 has the portions 55 26a between the notches formed in its thin side portion bent reversely to form a bight 26b as shown. This bight is also adapted to receive the locking wire 25 as shown in Fig. 10. The bights 22a or 26b may have a depression 26c formed therein which will be made by pressing inwardly on the convex side of the bight. This can be done by a press or hammer. This moves the bottom of the bight farther rearwardly on the post so that the locking wire or rod 25 must 60 pass around the same. This springs the locking wire to the rear so that it will press rearwardly on the strands of fence wire and move the same to the rear of the slots 22b and the slots between portions 26a. It is desirable to have the fence wires so held to avoid excessive vibration due to the wind or other causes.

In Fig. 12 the post as shown in Figs. 9 and 10 is illustrated but instead of using the locking wire 25, a locking member in the form of a wedge 75 31 is used. Due to the shallow bight or trough

this wedge can readily be inserted at the outer side or rear of the post and driven down in front of the strand 24 of the fence. The wedge is preferably roughened as shown at 31a on its straight side in order to give more friction. Such a fastening means has the advantage that if a broken wire is to be replaced in the fence the locking wire or rod 25 will not have to be removed from all of the wires but only the particular wedge holding the wire will have to be removed. 10

In Figs. 14 and 15 the strands 27 of the fence are shown extending horizontally while the vertically extending fence wires are shown as 28. These are connected by another wire or clip 29. The vertical wires 28 are disposed within the bight 26b, the locking wire 25 also being disposed in the bight farther toward the edge of the post. An additional support is thus given to the fence should an outward stress occur due to the wind, snow, or an animal rubbing thereagainst. 20

In Fig. 13 a chicken wire or netting is shown attached to the post. It will be seen that the twisted portions 30 of the netting can be disposed in the slots 22b or in the slots between portions 26a and the locking wire 25 passed in front of 25 the same.

From the above description it is seen that applicant has provided a simple and highly efficient structure of post. By having the thin edge portion it is much easier to cut the posts from the blank and it is much easier to bend the thin edge portion into the bight or trough form. The thin edge portion also saves metal. By having the post cut from the blank shown in Figs. 2 and 3 the notches are easily formed in the thin edge 35 portion. It is pointed out that the slots in the thin edge portion extend entirely to the edge of the bent-over or bight portion. When the locking wire 25 is placed in the post it is inserted from the top. With the shallow open channel or 40 groove formed by the bight portion the end of the wire can be readily engaged by one hand and the wire quickly guided properly to pass over the fence wires. It will be seen that if the bight portion were longer and a slot merely cut through 45 the front or convex side of the bight portion so that there was metal at the end of the slot this would not be possible. It would also not be possible to have the vertical wires 28 of the fence disposed in the bight portion as shown in Figs. 50 14 and 15. With the bight or trough at the edge of the post entirely open at the rear it is also possible to cut the post from the blank shown in Figs. 2 and 3. This would not be possible if the edge were merely formed into the trough and 55 slots cut through the convex side of the trough. The post can be cut from the blank as shown in Figs. 2 and 3 by either a cylindrical die roller or a straight punching die. In punching slots in thick metal the metal adjacent the slots is often 60 cracked and injured, seriously weakening the post and causing a weak spot therein. The post is quite apt to fail at this weak spot. This shock and injury to the post is avoided by having the edge portion thin in which the slots are cut. The 65 thin edge portion also makes it possible to have more metal in the post where it is needed at the vertex of the angle or bight. By having the thin portion extend out flat at the ground end of the post it is easier to drive the post into the 70 ground and a large area is obtained for anchoring purposes. It is desirable to have the tongues 22c adjacent the ground portion if wires are to be placed against the ground. It will be seen that the wires can readily be placed under the 75

5 tongues and as above stated the ends of the tongues can be bent around the lower side of the wire. All of the wires on the fence thus extend transversely of the post and there is no appreciable kinking or bending of any of the wires in the post or by the fastening means. In the form of post shown in Figs. 1 to 6 the fence wires also bear against the front edge of the post which does not have the bight thereon, thus giving additional bearing surface to the fence to resist any pressure inwardly toward the post.

10 The post has been amply demonstrated in actual practice and found to be very successful and efficient.

15 It will, of course, be understood that various changes may be made in the form, details, arrangement and proportions of the parts, without departing from the scope of applicant's invention, which generally stated, consists in a device 20 capable of carrying out the objects above set forth in the parts and combinations of parts disclosed and defined in the appended claims.

25 What is claimed is:—

1. A fence post of angular form in cross section and made of plate-like material, said post having vertically spaced notches cut in one side

thereof, the portions between said notches being reversely bent to form a shallow bight or trough adapted to receive a vertically extending locking member, said notches extending to and through the vertical edge of said side so that the horizontal strands of a wire fence may be disposed therein and the vertical strands of said fence may be disposed in said bight or trough whereby the fence can be held by said post over a wide vertical extent and said locking member is very 10 accessible in said bight or trough.

2. A fence post of angular form in cross section and made of plate-like material, said post having vertically spaced notches cut in one side 15 thereof, the portions between said notches being reversely bent to form a shallow bight or trough adapted to receive a vertically extending locking wire so that the horizontal strands of a wire fence can be disposed in said notches in the rear of said locking wire, said bight having one or 20 more depressions formed therein at its convex side around which said locking wire must pass to place tension on said locking wire and cause the same to move said fence strands against the rear side of said notches so that they will be 25 firmly held again vibration.

EDWARD PAVEK.
